UNITED STATES PATENT OFFICE.

ERNEST B. BISHOP, OF MIDDLETON, CONNECTICUT, ASSIGNEE, BY MESNE ASSIGNMENTS, TO THE NOISELESS TYPEWRITER COMPANY, OF MIDDLETON, CONNECTICUT, A CORPORATION OF CONNECTICUT.

TYPE-WRITING MACHINE.

1,120,676.

Specification of Letters Patent. Patented Dec. 15, 1914.

Application filed March 22, 1910. Serial No. 550,955.

To all whom it may concern:

Be it known that I, ERNEST B. BISHOP, a citizen of the United States, residing at Middletown, in the county of Middlesex 5 and State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and with regard to the more specific features thereof, to space bar mechanism.

One of the objects of the present invention is to provide a simple and practical device which will be efficient in operation.

Another object is to construct a device of the above nature which will be silent in its 20 operation.

A further object is to provide a device of the above nature which will permit an easy action and a substantially vertical movement of the space bar.

A further object is to provide a device of the above nature of a few number of parts that will be cheap to manufacture.

A further object is to provide for a uniformity of action among the moving parts.

Other objects will be in part obvious and in part hereinafter pointed out.

The invention accordingly consists in the features of construction, combinations of elements and arrangement of parts which 35 will be exemplified in the construction hereinafter set forth, and the scope of the application of which will be indicated in the following claims.

In the accompanying drawings, wherein is 40 shown one of many possible embodiments of the present invention, Figure 1 represents a side elevation of a typewriter sufficient to illustrate an embodiment of the present invention applied thereto; Fig. 2 is a plan view of the same.

Similar reference characters refer to similar parts throughout the several views of the drawings.

While the present invention is illustrated 50 and described with reference to that form of a typewriting machine known as the Noiseless typewriter, it is, of course, to be understood that the mechanism illustrated and described herein may be applied to

any form of a typewriter without materially altering or modifying the construction.

Referring to these drawings in detail, 1 represents a space bar located in front of the key board supported by space bar levers 2 and 3 which pass below the various actuating parts of the machine to substantially the rear of the frame, where they are fulcrumed on pins 4 supported by depending lugs 5 and 6 secured to the frame of the machine. Intermediate the arms 2 and 3 is 65 positioned a cross brace 7 for stiffness and also furnishing a means of connection for a pull wire 8 secured at one end 9 thereto and to a false key or spacing lever 10 at the point 11. A clip 12 is provided for holding 70 the end of the pull wire 8 in engagement with the spacing lever 10. This lever 10 is fulcrumed at one end on a knife edge 13 after passing through a slot in a comb 14, and is securely held in place by means of a 75 pivoted roller 15 suspended from brackets 16 at either side of the slot to prevent misplacement at this point when the space bar is actuated. A spring 17 is adjustably mounted at one end in the comb and inserted 80 through a hole in the spacing lever 10 for holding the same in normal position. It is to be noted that this spring aids in returning the parts to normal position when the same have been actuated by the space bar. 85

The lever 10 is similar in general construction to any key lever, only one of which, 10', is shown, and is guided in a vertical direction at its forward end by means of a comb 18 for the key levers secured to 90 any convenient part of the frame of the machine. It is provided with a foot 19 adapted to contact with a pad 20 mounted on a universal bar 21 when the lever is actuated. A slight space is preferably provided between the foot of the spacing lever 10 and the pad 20 on the universal bar, as well as between the key levers 10' and the pad, to prevent a contact with the others when actuated by one, thereby preventing a needless 95 rattle and jar of the key levers at each impression.

The space bars and spacing lever being connected by pull wire 8 will actuate the universal bar in the same manner as the 105 actuation of the key lever 10', thereby giving a uniformity of action among these moving parts. This universal bar may be

of any desired construction, but that form illustrated and described in the pending application of J. A. Ronchetti, Serial No. 436,749, filed June 5, 1908, for typewriting machines, with the silent stop shown therein, is believed to be especially advantageous for use in this relation. The lower part of this universal bar is provided with a pad 22 adapted to engage a bracket 23 secured to the frame in such manner that it is permitted to have a free and unrestricted movement in a downward direction and yet be silently arrested on its return to normal position. The arms 2 and 3 of the space bar are each provided with an upwardly projecting foot 24 adapted to engage pads or other silencing means 25 secured to the frame immediately behind the brackets 23. These spacing levers 2 and 3 are guided in their vertical movement by means of slots in the under side of the comb 18.

A stop 26 secured to the forward part of the frame is preferably provided for the space bar to silently arrest the same on its downward movement. This stop may be made adjustable as at 27 if desired, should it be found necessary to adjust the stroke at any time. The universal bar 21 is suspended by means of links 28 from arms 29 rigidly secured to the universal rock shaft 30. Projecting rearwardly from this rock shaft and also secured rigidly thereto is an arm 31 connected by means of a spring 32 with any convenient fixed part of the machine 33 for normally holding the universal bar and associated parts in raised position. A third arm 34 on the universal rock shaft 30 is adapted to be connected to the vibratory rocker member of the spacing mechanism, which it is believed is unnecessary to illustrate in this application.

The operation and manner of use of this device is substantially as follows: The space bar 1 being positioned at such a relatively large distance from its pivot point, it moves in almost a vertically straight line when depressed and carries with it the spacing lever 10, which is connected therewith by means of the pull wire 8. When the spacing lever 10 is depressed the foot 19 contacts silently with the pad 20 on the universal bar 21 and depresses the same to actuate the universal rock shaft 30, which, through connecting mechanism, actuates the spacing mechanism, not herein shown. When the spacing lever 10 is depressed the spring 17 will be tensioned, and also the spring 32 connected with the arm 31 upon the universal rock shaft. These springs will aid one another in returning the parts to normal position as soon as pressure on the space bar 1 is released. As the parts return to normal position the space bar levers 2 and 3 will contact with the silencing pad 25 on the frame of the machine, and the pad 22 at the lower

part of the universal bar 21 will contact with the bracket 23 on a fixed part of the machine in such manner as to silently arrest both of these parts. A slight space being provided between the upper surface of the pad 20 on the universal bar and the key levers and spacing lever 10 prevents the same from coming in contact therewith to cause needless rattle and jar of the actuating parts.

It is thus seen that this invention provides for a simple and practical construction in which the space bar has an almost vertical movement due to the fact that its pivot is at the rear of the frame of the machine and the arc through which it travels is therefore almost imperceptible. Various silencing means associated with the actuating parts of the mechanism enable the spacing mechanism to be actuated without noise and in a speedy and efficient manner.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, a space bar, a universal bar adapted to have a movement independent of said space bar, means above said universal bar adapted to coact therewith, and a connection between said means and said space bar whereby the universal bar is actuated on depression of said space bar.

2. In a typewriting machine, in combination, a pivotally supported space bar, a universal bar above said space bar, a movable member resting above said universal bar, and connecting means between said member and said space bar whereby motion is transmitted from one to the other to actuate the spacing mechanism when said space bar is depressed.

3. In a typewriting machine, in combination, a pivoted space bar adapted to have a substantially vertical movement, means for guiding the movement of said space bar, a universal bar, a spacing lever and key levers resting above said universal bar, and connecting means between said spacing lever and said space bar for giving uniformity of action among said moving parts.

4. In a typewriting machine, in combination, a pivotally mounted space bar adapted to move in a substantially vertical line, a universal bar, a spacing lever and key levers resting above said universal bar, connections between said spacing lever and said

- space bar for giving uniformity of action among said moving parts, and a silent stop for arresting the upward movement of said pivotally mounted space bar.
5. In a typewriting machine, in combination, a pivotally mounted space bar, a universal bar, a spacing lever above said universal bar, a knife edge on which said spacing lever is pivoted, and intermediate connections between the spacing lever and the space bar for actuating the former when said space bar is depressed.
10. In a typewriting machine, in combination, a pivotally mounted space bar, a spacing lever, a universal bar intermediate the pivotally mounted space bar and said spacing lever and out of contact with both, and connections whereby the universal bar is actuated through said spacing lever upon depression of the space bar.
15. In a typewriting machine, in combination, a pivotally mounted space bar, a spacing lever, a moving part intermediate said space bar and said spacing lever and out of contact with both, and connections between the spacing lever and the space bar whereby the former is moved into contact with the moving part to actuate the same when said space bar is depressed.
20. In a typewriting machine, in combination, a pivotally mounted space bar, a spacing lever, depending means on which said spacing lever is mounted, means for holding said spacing lever upwardly in contact with said means, and connections between the spacing lever and the space bar whereby the former is moved when said space bar is depressed.
25. In a typewriting machine, in combination, a pivotally mounted space bar, a spacing lever, a knife edge on which said spacing lever is mounted, means for holding said spacing lever in contact with said knife edge, connections between the spacing lever and the space bar whereby the former is moved when said space bar is depressed, and means for returning said parts to normal position.
30. In a typewriting machine, in combination, a pivotally mounted space bar, a pivotally mounted spacing lever, a universal bar intermediate the same and out of contact with both, connections between the space bar and spacing lever transmitting motion from one to the other, and means for silently arresting the movement of said parts.
35. In a typewriting machine, in combination, a universal bar, a lever above said bar, finger-actuated means below said universal bar, and means connecting the parts above and below the universal bar, whereby a uniformity of action takes place between said parts.
40. In a typewriting machine, in combination, a frame, a space bar pivotally mounted on said frame, a spacing lever pivotally mounted on said frame, connections between said parts, and a single spring engaging one of said members for returning said space bar and spacing lever to normal position when actuated.
45. In a typewriting machine, in combination, a frame, a space bar pivotally mounted on said frame, a spacing lever pivotally mounted on said frame, connections between said parts, the universal bar beneath said spacing lever adapted to be actuated thereby, and means on said frame adapted to silently arrest the movement of one of said parts when returning to normal position.
50. In a typewriting machine, in combination, a frame, a space bar pivotally mounted on said frame, a spacing lever pivotally mounted on said frame, connections between said parts, a universal bar between the space bar and the spacing lever, a pad on said universal bar, and means on said frame adapted to engage said pad to silently arrest the movement of said universal bar.
55. In a typewriting machine, in combination, a frame, a pivotally mounted space bar, a pivotally mounted lever thereabove, and a comb secured to said frame having teeth pointed in opposite directions adapted to guide the movement of said space bar and lever.
60. In a typewriting machine, in combination, a frame, a pivotally mounted space bar, a pivotally mounted spacing lever, a comb secured to said frame having teeth pointed in opposite directions adapted to guide the movement of said space bar and spacing lever, and a connecting member between said space bar and said spacing lever whereby the same are actuated simultaneously.
65. In a typewriting machine, in combination, a frame, a pivotally mounted space bar, a pivotally mounted spacing lever and key levers, a comb secured to said frame having teeth pointed in opposite directions adapted to guide the movement of said space bar and levers, a connecting member between said space bar and said spacing lever whereby the same are actuated simultaneously, and a universal bar adapted to be engaged by said spacing lever.
70. In a typewriting machine, in combination, a frame, a space bar pivotally mounted on said frame, a spacing lever pivotally mounted on said frame, connections between said parts, and a single spring engaging one of said members for returning said space bar and spacing lever to normal position when actuated.
75. In a typewriting machine, in combination, a frame, a space bar pivotally mounted on said frame, a spacing lever pivotally mounted on said frame, connections between said parts, the universal bar beneath said spacing lever adapted to be actuated thereby, and means on said frame adapted to silently arrest the movement of one of said parts when returning to normal position.
80. In a typewriting machine, in combination, a frame, a space bar pivotally mounted on said frame, a spacing lever pivotally mounted on said frame, connections between said parts, a universal bar between the space bar and the spacing lever, a pad on said universal bar, and means on said frame adapted to engage said pad to silently arrest the movement of said universal bar.
85. In a typewriting machine, in combination, a frame, a pivotally mounted space bar, a pivotally mounted lever thereabove, and a comb secured to said frame having teeth pointed in opposite directions adapted to guide the movement of said space bar and lever.
90. In a typewriting machine, in combination, a frame, a pivotally mounted space bar, a pivotally mounted spacing lever, a comb secured to said frame having teeth pointed in opposite directions adapted to guide the movement of said space bar and spacing lever, and a connecting member between said space bar and said spacing lever whereby the same are actuated simultaneously.
95. In a typewriting machine, in combination, a frame, a pivotally mounted space bar, a pivotally mounted lever thereabove, and a comb secured to said frame having teeth pointed in opposite directions adapted to guide the movement of said space bar and lever.
100. In a typewriting machine, in combination, a frame, a pivotally mounted space bar, a pivotally mounted spacing lever, a comb secured to said frame having teeth pointed in opposite directions adapted to guide the movement of said space bar and spacing lever, and a connecting member between said space bar and said spacing lever whereby the same are actuated simultaneously.
105. In a typewriting machine, in combination, a frame, a pivotally mounted space bar, a pivotally mounted lever thereabove, and a comb secured to said frame having teeth pointed in opposite directions adapted to guide the movement of said space bar and lever.
110. In a typewriting machine, in combination, a frame, a pivotally mounted space bar, a pivotally mounted spacing lever and key levers, a comb secured to said frame having teeth pointed in opposite directions adapted to guide the movement of said space bar and levers, a connecting member between said space bar and said spacing lever whereby the same are actuated simultaneously, and a universal bar adapted to be engaged by said spacing lever.
115. In a typewriting machine, in combination, a frame, a pivotally mounted space bar, a pivotally mounted lever thereabove, and a comb secured to said frame having teeth pointed in opposite directions adapted to guide the movement of said space bar and lever.
120. In a typewriting machine, in combination, a frame, a pivotally mounted space bar, a pivotally mounted spacing lever, a comb secured to said frame having teeth pointed in opposite directions adapted to guide the movement of said space bar and spacing lever, a connecting member between said space bar and said spacing lever whereby the same are actuated simultaneously, and a universal bar adapted to be engaged by said spacing lever.
125. In a typewriting machine, in combination, a frame, a pivotally mounted space bar, a pivotally mounted lever thereabove, and a comb secured to said frame having teeth pointed in opposite directions adapted to guide the movement of said space bar and lever.
130. In a typewriting machine, in combination, a frame, a pivotally mounted space bar, a pivotally mounted spacing lever, a comb secured to said frame having teeth pointed in opposite directions adapted to guide the movement of said space bar and spacing lever, a connecting member between said space bar and said spacing lever whereby the same are actuated simultaneously, and a universal bar adapted to be engaged by said spacing lever.

spacing lever, and means for silently arresting the movement of one of said parts.

19. In a typewriting machine, in combination, a frame, a pivotally mounted space bar, a pivotally mounted spacing lever, a comb secured to said frame having teeth pointed in opposite directions adapted to guide the movement of said space bar and spacing lever, a connecting member between said space bar and said spacing lever whereby the same are actuated simultaneously, a universal bar adapted to be engaged by said spacing lever, and means for silently arresting the movement of said space bar.

20. In a typewriting machine, in combination, a frame, a pivotally mounted space bar, a pivotally mounted spacing lever, a comb secured to said frame having teeth pointed in opposite directions adapted to guide the movement of said space bar and spacing lever, a connecting member between said space bar and said spacing lever whereby the same are actuated simultaneously, a universal bar adapted to be engaged by said spacing lever, and means for silently arresting the movement of said universal bar.

21. In a typewriting machine, in combination, a frame, a pivotally mounted space bar, a pivotally mounted spacing lever, a comb secured to said frame having teeth pointed in opposite directions adapted to guide the movement of said space bar and spacing lever, a connecting member between said space bar and said spacing lever whereby the same are actuated simultaneously, a universal bar adapted to be engaged by said spacing lever, and a spring means for returning said space bar and spacing lever to normal position.

22. In a typewriting machine, in combination, a frame, a pivotally mounted space bar, a pivotally mounted spacing lever, a comb secured to said frame having teeth pointed in opposite directions adapted to guide the movement of said space bar and spacing lever, a connecting member between said space bar and said spacing lever whereby the same are actuated simultaneously, a universal bar adapted to be engaged by said spacing lever, and spring means adapted to engage one of said parts for returning a plurality of said parts to normal position.

23. In a typewriting machine, in combination, a pivotally mounted space bar, a pivotally mounted lever, roller means for holding said lever in position against its pivoted point, and connections between said space bar and lever whereby one is actuated from the other.

24. In a typewriting machine, in combination, a pivotally mounted space bar, a pivotally mounted lever, roller means for holding said lever in position against its fulcrum, connections between said space bar and lever whereby one is actuated from the

other, and a universal bar intermediate the space bar and lever adapted to be actuated by the latter on depression of the former.

25. In a typewriting machine, in combination, a pivotally mounted space bar, a pivotally mounted lever, roller means for holding said lever in position against its fulcrum, connections between said space bar and lever whereby one is actuated from the other, and a universal bar beneath said lever adapted to be actuated by the latter on depression of the former.

26. In a typewriting machine, in combination, a pivotally mounted space bar, a pivotally mounted lever, roller means for holding said lever in position against its fulcrum, connections between said space bar and lever whereby one is actuated from the other, a universal bar intermediate the space bar and lever adapted to be actuated by the latter on depression of the former, and means for silently arresting the movement of said parts.

27. In a typewriting machine, in combination, a pivotally mounted space bar, a pivotally mounted lever, roller means for holding said lever in position against its fulcrum, connections between said space bar and lever whereby one is actuated from the other, a universal bar intermediate the space bar and lever adapted to be actuated by the latter on depression of the former, and padded means adapted silently to arrest the movement of said parts.

28. In a typewriting machine, in combination, a pivotally mounted space bar, a pivotally mounted spacing lever, roller means for holding said lever in position against its fulcrum, connections between said space bar and spacing lever whereby one is actuated from the other, a universal bar intermediate said space bar and spacing lever and out of contact with both adapted to be actuated by the latter on depression of the former, padded means adapted silently to arrest the movement of said parts, and a spring adapted to engage one of said parts for returning the same to normal position.

29. In a typewriting machine, in combination, a pivotally mounted space bar, a pivotally mounted spacing lever, roller means for holding said lever in position against its fulcrum, connections between said space bar and spacing lever whereby one is actuated from the other, a universal bar intermediate said space bar and spacing lever and out of contact with both adapted to be actuated by the latter on depression of the former, padded means adapted silently to arrest the movement of said parts, and spring means operatively associated with said spacing lever to aid in returning said space bar to normal position.

30. In a typewriting machine, in combi-

- 5 nation, a pivotally mounted space bar, a pivotally mounted spacing lever, roller means for holding said lever in position against its fulcrum, connections between said space bar and spacing lever whereby one is actuated from the other, a universal bar intermediate said space bar and spacing lever and out of contact with both adapted to be actuated by the latter on depression of the former, padded means adapted silently to arrest the movement of said parts, a spring adapted to engage one of said parts adapted to aid in returning a plurality of said parts to normal position, and a single member adapted to guide the movement of said space bar and spacing lever.
- 10 31. In a typewriting machine, in combination, a space bar, a lever connected therewith, a universal bar intermediate the same, and means whereby the space bar actuates the universal bar through said lever when depressed an amount substantially equal to the actuation of said lever.
- 15 32. In a typewriting machine, in combination, a space bar, a spacing lever, a universal bar intermediate the same and out of contact with both, connecting means between the space bar and spacing lever whereby the spacing lever engages and actuates the universal bar when the space bar is depressed, and means for silencing the contact between the spacing lever and the universal bar.
- 20 33. In a typewriting machine, in combination, a space bar, key and spacing levers, a universal bar intermediate the same and out of contact therewith, connecting means between the space bar and spacing lever
- 25 whereby the spacing lever engages and actuates the universal bar when the space bar is depressed, means for silencing the contact between the spacing lever and the universal bar when the space bar is depressed, means for silencing the contact between the spacing lever and the universal bar, and means for silently arresting the return movement of said parts.
- 30 34. In a typewriting machine, in combination, a frame, a universal bar, and means coacting directly with the under part of said universal bar, adapted silently to arrest the upward movement of said universal bar on its return to normal position.
- 35 35. In a typewriting machine, in combination, a frame, a universal bar, and a pad carried beneath the effective surface of said bar adapted to engage a portion of said frame for silently arresting the movement thereof.
- 40 36. In a typewriting machine, in combination, a frame, a bracket on said frame, a universal bar, and a pad carried by said universal bar at the lower part thereof and beneath its effective surface adapted to engage said bracket and silently arrest the return movement thereof.
- 45 37. In a typewriting machine, in combination, a universal bar, actuating mechanism therefor including a pivoted lever, a knife edge on which said lever is pivoted, and roller means opposite said knife edge for holding said lever in engagement therewith.
- 50 55 60 65 70
- In testimony whereof I affix my signature, in the presence of two witnesses.

ERNEST B. BISHOP.
